Inventor,
Wm. W. Campbell,

UNITED STATES PATENT OFFICE.

WILLIAM W. CAMPBELL, OF CAMBRIA, INDIANA.

FENCE.

SPECIFICATION forming part of Letters Patent No. 399,833, dated March 19, 1889.

Application filed August 22, 1888. Serial No. 283,409. (No model.)

To all whom it may concern:

Be it known that I, WILLIAM W. CAMPBELL, a citizen of the United States, residing at Cambria, in the county of Clinton and State of Indiana, have invented a new and useful Improvement in Fences, of which the following is a specification.

The object of this invention is to provide a simple, cheap, durable, and portable fence which may be readily erected and taken apart; and it consists in a certain novel construction and arrangement of devices, fully set forth hereinafter in connection with the accompanying drawings, and specifically pointed out in the appended claim.

In the drawings, Figure 1 is a perspective view of a section of the improved fence. Fig. 2 is a side view of a portion of the same, partly in section.

Referring by letter to the drawings, A A designate small transverse sills or blocks, which are arranged on or in the ground, with their upper sides projecting slightly above the surface of the ground, and in the said sills or blocks are formed sockets *a a*.

The posts B B are provided at their lower ends with slightly-reduced extensions *b b*, which are seated in these sockets *a a*, and C C are small blocks secured on the sides of the posts, near their upper ends, which are provided with depressions or sockets *c c*.

The separable detachable panels D D consist of the horizontal rails *d d'*, to which are secured the vertical pickets E E, the said panels being formed before applying them to the posts. The ends of the upper rails, *d*, are provided with the depending pins *e*, which engage the sockets *c c* in the blocks C C, and the lower rails, *d'*, are also provided with depending pins *e'*, which engage in similar sockets, *c'*, in the sills or blocks adjacent to the lower end of the post. The end pickets of the panels are extended upwardly, and their ends are connected by the longitudinal wire, which aids in strengthening the separate panels.

As will be readily seen, the fence is constructed as follows: The sills or blocks are

first arranged at the proper intervals, determined by the lengths of the panels. The lower ends of the posts are then seated in the sockets *a* in the sills or blocks, after which the depending pins on the ends of the horizontal rails of the panels are engaged in the sockets *c* and *c'*, which are formed, respectively, in the blocks C and the sills or blocks. The ends of the horizontal rails of adjoining panels bear against each other, and thus brace the fence longitudinally, and the fence is braced laterally, from the fact that the ends of the bottom rails of the panels rest on the sills or blocks and bear against the sides of the post.

It will be obvious that the fence is simple and is easily erected, and when it is desired to move it the panels are readily removed and replaced.

A further advantage of this fence, when used on farms to inclose pastures, is that the panels may be readily removed to form a passage to permit the entrance or exit of cattle or stock.

Having thus described my invention, I claim—

In a portable fence, the combination of the sill placed on the ground transversely to the line of the fence and having sockets *a* and *c'*, the posts having reduced lower ends secured in the sockets *a*, and having blocks C attached to their front sides and provided with recesses *c*, and the panels composed of pickets connected by horizontal upper and lower rails, which rest, respectively, upon the blocks C and the sills, and are provided with downwardly-extending pins entering the sockets *c c'*, said horizontal rails being of such length that the ends of the rails of adjoining panels shall abut against each other, substantially as set forth.

In testimony that I claim the foregoing as my own I have hereto affixed my signature in presence of two witnesses.

WILLIAM W. CAMPBELL.
